UNITED STATES PATENT OFFICE.

CHARLES W. RENNER, OF ALTOONA, PENNSYLVANIA.

METAL DOOR.

1,159,993.

Specification of Letters Patent.

Patented Nov. 9, 1915.

Application filed July 10, 1914. Serial No. 850,222.

To all whom it may concern:

Be it known that I, CHARLES W. RENNER, a citizen of the United States, residing at Altoona, in the county of Blair and State 5 of Pennsylvania, have invented new and useful Improvements in Metal Doors, of which the following is a specification.

The invention relates to an improvement in metal doors, and particularly to a door 10 cast in two sections.

In the present invention, the improved door is constructed with a view to providing a cast structure made up of two sections, wherein provision is made for the 15 locks, hinges, and for properly bracing the sections when they are assembled in door forming relation.

The invention in the preferred form of details will be described in the following 20 specification, reference being had particularly to the accompanying drawings, in which:—

Figure 1 is a view in elevation, partly 25 broken out of the improved door. Fig. 2 is an enlarged broken section on the line 2—2 of Fig. 1. Fig. 3 is an enlarged broken elevation, showing one corner of the door structure. Fig. 4 is a section on the line 30 4—4 of Fig. 3. Fig. 5 is an enlarged elevation, showing the lower corner of the door structure. Fig. 6 is an elevation partly 35 broken out of a portion of the door structure, showing the lock housing. Fig. 7 is a section on line 7—7 of Fig. 6. Fig. 8 is a broken sectional view through the door structure.

In constructing the improved door, the 40 respective sections are made up as castings, though it is to be understood that there is no limitation intended herein as confining the invention to a cast door.

The door proper is constructed of two sections 1 and 2, each forming approximately one-half of the door structure, divided centrally and longitudinally, so that one section 45 includes the outer face of the door and the other section the inner face. The section 1, which will be termed the main section, is formed to provide offsets 3 forming the lower rail of the door, side offsets 4 forming the stiles, an intermediate offset 5 forming the central rail of the door and the upper offset 6 forming the upper rail of the door. The space intermediate the lower 55 and center rails and the stiles is in the particularly shown type of door illustrated

formed to provide an integral panel 7, the material of the panel being in the center line of the door. The space between the center and upper rails and the stiles is in 60 the particular type of door shown free of connection to provide for the reception of the removable panel 8, such as glass or the like, the construction for securing which will later appear. The edges of the door forming the margin of the section 1 are turned inwardly to provide one-half the thickness of the door forming the side and end edges as at 9.

The section 2 is practically a duplicate of 70 the section 1 having the offsets to form the hanging and lock stiles, and the upper section and lower rails. In this instance, the panel strip 7 is omitted, the panel strip of 75 the section 1 serving as the panel formation. Furthermore, the inner marginal edge of the section 2 for the upper and center rails and the side stiles is formed to provide a slight extension beyond the similar edge of the section 1, whereby to form a projecting shoulder or ledge 10, against which the panel 8 rests when in position, as will 80 later appear.

The hollow sections forming the rail and 85 stile offsets are in their casting formed with transverse and longitudinally extending 90 ribs 11, coextensive in height with the similar dimension of the offset, and similarly arranged in each door section, as clearly shown 95 in Fig. 4. These ribs abut squarely when the sections are assembled and at appropriate 100 points throughout the offsets each section is formed therein with enlargements 12 in the form of bosses each of which is formed with a suitable opening 13, so that when the sections are assembled, rivets 14 or other securing means may be readily applied. The outer wall of the hanging stile offset is thickened at appropriate points as at 15 to 105 provide for securing hinges 16 thereto, as shown in Figs. 3, 4, and 5. At an appropriate point in the lock stile, the offsets of the respective sections are formed with spaced parallel ribs 17 formed when the sections are assembled to provide a mortise 110 18 to receive the lock 19.

With the door sections assembled, the upper panel 8 is placed in position resting against the shoulders or ledges 10, and the angle plate 20 is secured against the opposed 110 side of the panel resting upon the marginal edge of the side and stiles and upper and

lower rail of the section 1, being secured in place by screw bolts 21.

The improved door is constructed in two sections, and these two sections are so formed as to present practically complete a metal door in which necessary reinforcement is properly provided for and provision made for securing all necessary attachment.

What is claimed is:—

- 10 1. A metal door made in two sections, each including one face of the door, each section being formed with offsets to provide a portion of the respective rails and a portion of the stiles, the interior of each offset being formed with integral strengthening ribs and with riveting bosses, the ribs and bosses of the respective sections being coextensive in height with the depth of the offsets and abutting when the sections are assembled.
- 15 2. A metal door made in two sections, each including one face of the door, each section being formed with offsets to provide a portion of the respective rails and a portion of the stiles, coöperating stile offsets of each section being formed with spaced parallel ribs to abut when the sections are assembled for forming a lock mortise.
- 20 3. A metal door formed in two sections each including one face of the door, each section being formed with offsets to provide upper, center and lower rails and stiles, one section in the space between the stiles, lower

and center rail having an integral plate to form a panel, the space of one section between the stiles, upper and central rails being open and presenting a marginal edge at right angles to the face of the respective sections, the edge of the other section corresponding to such open portion of the first mentioned section being extended inwardly beyond said marginal edge to form a ledge.

4. A metal door formed in two sections each including one face of the door, each section being formed with offsets to provide upper, center and lower rails and stiles, one section in the space between the stiles, lower and center rail having an integral plate to form a panel, the space of one section between the stiles, upper and center rails being open and presenting a marginal edge at right angles to the face of the respective sections, the edge of the other section corresponding to such open portion of the first mentioned section being extended inwardly beyond said marginal edge to form a ledge, and a removable panel bearing on said ledge, and means engaging such marginal edge for securing the panel in place.

In testimony whereof I affix my signature in presence of two witnesses.

CHARLES W. RENNER.
